[57] **ABSTRACT**

An illuminated display stand of the type adapted for revolving display of a plurality of wigs, as well as cosmetic containers. The stand includes a plurality of vertically extending perforated rods, drive means for rotating the rods and a plurality of hooks or clips engageable within the perforations of the rods and extending radially to support a stand either for human wigs or cosmetic display. Aseptizing lamps, such as UV lamps may be used in connection with the illuminated display.

ILLUMINATED DISPLAY STAND FOR WIGS AND COSMETICS

BACKGROUND OF THE INVENTION

1. Field of the Invention

Display housing for wigs and cosmetics, including a drive means for rotating the displayed articles throughout 360°.

Numerous previous inventors have addressed themselves to the problem of displaying cosmetics, wigs, camera film or the like by the use of an open revolving cage with bracket supports. However, the prior art has not addressed itself to the problem of displaying a plurality of wigs simultaneously, or in a manner that they might be classified together as to hair or styling type.

2. Description of the Prior Art

Prior art searching has developed:

Bair	1,080,530
Carter	1,243,706
Martin	2,091,867
Liska	2,270,757
Baren	2,883,063
Winter, Jr.	2,887,232
Bleed	3,223,247

Bair shows an upper cage-like structure with support brackets; however the case and center pivot mechanism are different. The Bleed, Winter, Baren and Carter patents show various types of rotatable drum displays involving mounting brackets. Martin and Liska show drum type displays and with interior illumination.

SUMMARY OF THE INVENTION

According to the present invention the illuminated display stand includes a base, a drive means supported in the base, and a plurality of vertically extending perforated display rods rotatably journaled in the base, so as to engage the drive means. Display hook means are engageable with the perforations in the display so as to extend radially outwardly thereof as a cosmetic or wig support. Human head forms or horizontal shelves may be supported upon the display supports. Aseptic lamp means may be provided so as to maintain the wigs and cosmetics in sterile condition. The device is characterized in its relatively simple, yet durable and reliable mode for rotating the individual displays throughout 360°. As a result, the wig purchaser, for example, might simultaneously view as many as 48 different wigs, categorized or classified as to color or hair styling upon different vertically extending rods. Conventionally, wigs are individually displayed by removal from the box, a time consuming and damaging process which affords scant opportunity for shopper comparison.

Modifications of invention include a lower rotating display stand for cosmetics and using the display hooks as shelf supports for cosmetic display, such as hair rinses.

BRIEF DESCRIPTION OF THE DRAWINGS

FIG. 1 is a perspective view of the stand, showing wig display forms in phantom;

FIG. 2 is a vertical section thereof;

FIG. 3 is a top plan;

FIG. 4 is a transverse section, taken along section line 4-4 of FIG. 2; and configured to engage implementally the interior of a human head form.

FIG. 5 is an enlarged perspective of one type of display hook.

DESCRIPTION OF THE PREFERRED EMBODIMENTS

In FIG. 1 the illuminated display housing is illustrated as including top lamp housing 10 and bottom housing 12 supported on a base stand 14, having laterally extending legs 16 and 18. The base may consist in radially extending angle irons 20 upon which is supported lower base plate 22. Within the base housing 12 place 36 supports drive motor 40 and mounting blocks 42. Motor 40 has bevel laterally extending shaft 44 to which is attached bevel driving gear 46 in turn engaging driven gear 48. Axial shaft 50 extends from driven gear 46 to top drive plate or spur 56, having peripheral teeth 58 which engage corresponding teeth 60 at the bottom of vertically extending perforated rods 26, 28, 30 and 32. The rods may be journaled in ball bearings 61 and 63 at their bottom and may be journaled to corresponding ball bearings 76 and 78 in the lamp housing top 10. Plate 36 positioned in the bottom of housing 20 may contain a reflective surface and a corresponding reflective surface 68, may be positioned in the top housing 10 as a reflection for conventional lamp 70. Also, an ultraviolet or similar aseptic illuminating lamp 74 may be mounted in conventional brackets. Similarly, in the bottom an ultraviolet or other illuminating light 38 may be mounted in conventional brackets 41.

The individual display brackets 62 are illustrated in FIG. 5 and may include a vertically extending portion 83 which fits complementally the interior of a head form so as to display wigs. Alternatively, the vertical portion 84 may be eliminated so that a circular disc may be applied as a cosmetic shelf support, as illustrated in FIG. 2. The bottom cosmetic display stand 54 may be mounted upon annular support 52 which is secured to the rotating lower plate 56, as a conventional cosmetic display. As will be apparent, the construction permits ease of comparison of the merchant's entire selection of cosmetics or wigs and results in saving of both display sales time, and eliminate the wear and damage accorded during conventional display of wigs.

Manifestly, the structure may be altered materially without departing from the spirit and scope of the invention.

I claim:

1. An illuminated display stand comprising:
  - a base;
  - drive means supported in said base;
  - a plurality of perforated and vertically extending display rods individually rotatable about their vertical axes while being journaled in said base, said display rods including drive elements engaging said drive means and
  - hook means engaging with the perforations in said display rods and extending laterally thereof as a display support.
2. An illuminated display stand as in claim 1, including a lamp housing journaled upon the upper ends of said vertically extending display rods.

3. An illuminated display stand as in claim 2, including at least one aseptic lamp positioned in said lamp housing.

4. An illuminated display stand as in claim 3, including an aseptic lamp positioned within said base, such that its illumination is reflected upwardly in parallel with said vertically extending rods.

5. An illuminated display stand as in claim 4, including lamp reflection means positioned both in said lamp housing and within said base.

6. An illuminated display stand as in claim 5, said drive means comprising an electric motor having a drive shaft and spur gear engageable with a rotatable plate journaled within said base axially with respect to said rotating rods, said spur gear having peripheral teeth engaging corresponding teeth in the lower ends of said vertically extending rods.

7. An illuminated display stand as in claim 6, including a lower display stand positioned upon said plate so as to be rotatable therewith and intermediate said verti-

20 cally extending rods.

8. An illuminated display stand as in claim 7, wherein said lower stand is adapted for cosmetic displays.

9. An illuminated display stand as in claim 8, wherein said hooks support head forms for simultaneous display of a plurality of wigs.

10. An illuminated display stand as in claim 9, said hooks extending radially with respect to said display rods and including a horizontally extending shelf.

11. An illuminated display stand as in claim 10, wherein both head forms with wigs and cosmetics are supported by means of said shelf extending radially with respect to said display rods.

12. An illuminated display stand as in claim 11, wherein the ends of said hooks are configured to engage the interior of a human head form.

13. An illuminated display stand as in claim 12, wherein the ends of said hooks are configured to be supported on said horizontal shelf.
